[57] CLAIM

The ornamental design for a multi-port cap fitting for a flask, as shown and described.

DESCRIPTION

FIG. 1 is a top perspective view of a multi-port cap fitting for a flask, showing our new design;

FIG. 2 is a top plan view thereof;

FIG. 3 is a bottom plan view thereof;

FIG. 4 is a left side elevational view thereof, the right side view being an identical view thereof; and

FIG. 5 is a front elevational view thereof, the rear view being a mirror thereof.
